UNITED STATES PATENT OFFICE.

LAWRENCE C. STEELE, OF PITTSBURGH, PENNSYLVANIA.

DOUBLING MACHINE.

Application filed November 22, 1922. Serial No. 602,573.

To all whom it may concern:

Be it known that I, LAWRENCE C. STEELE, a citizen of the United States, and resident of Pittsburgh, in the county of Allegheny and State of Pennsylvania, have invented a new and useful Improvement in a Doubling Machine; and I do hereby declare the following to be a full, clear, and exact description thereof.

10 My invention relates to machines and methods for doubling sheets of metal or other material, and it is designed particularly, although not exclusively, for doubling metal sheets during the process of rolling such sheets in packs.

One object of my invention is to provide an effective method of doubling metal sheets or packs of sheets by forming an initial bend or fold in the sheets, and then compressing this initial fold.

Another object of my invention is to provide an improved doubling machine of simple and rugged construction, which shall quickly and accurately double sheets or packs of sheets with a minimum of manual labor and at low cost.

My improved machine consists, in general, of two oscillating crimping members arranged adjacent to each other and having 30 cooperating working surfaces, together with a bending member arranged to engage the sheets along the line of doubling when the sheets are brought to the crimping members, and then to force the sheets between the crimping members and to give the sheets an initial bend along the line of doubling. The advancing movement of the bender acts through the sheets to rock the crimping members upon their pivots so as to produce 40 an opening through which the bender pushes the bent or folded portion of the sheets. Thereupon the bender is withdrawn from between the doubling members and the crimping members are then rocked in the reverse direction upon their pivots, thus engaging the sheets between the working surfaces of the crimping members and compressing the fold initially made by the bender along the line of doubling.

50 Other novel features of my invention relate to the manner in which the crimping members are oscillated in response to movement of the bending member, the manner in which the bending member is constructed and operated, and the manner in which the

superposed sheets are brought into proper position with relation to the crimping members and to each other.

In the embodiment of my invention here selected for illustration, the crimping members are arranged to rock on vertical axes and the bending member is pivotally mounted upon a slide which is reciprocated horizontally and which operates horizontal racks engaging pinions carried by the crimping members. It will be understood, however, that this particular arrangement of parts, while desirable, is not indispensable, and that, if desired, the axes of the crimping members may be otherwise than vertical, with corresponding changes in the position of the bender slide, and in the other operating mechanism.

In the accompanying drawing, Figure 1 is a plan view of a machine constructed in accordance with my invention; Fig. 2 is a longitudinal central sectional view of the same machine, the section being taken substantially on the line 2—2, Fig. 1, and the bender being shown in its horizontal position; Fig. 3 is another vertical sectional view, similar to a portion of Fig. 2, showing the rocking movement of the bender; Figs. 4 and 5 are plan views showing other positions of the operating parts; Fig. 6 is an enlarged cross-sectional view of the bender, bender slide and rack slide; Figs. 7, 8 and 9 are diagrammatic plan views illustrating three successive states in the doubling operation; and Fig. 10 is a diagrammatic plan view of a modified pair of crimping members.

In the drawing the numeral 2 indicates a suitable base or bed plate and the numeral 3 indicates a doubling table which is mounted a suitable distance above the bed plate 2 to provide room for the operating mechanism. The upper surface of the doubling table 3 is preferably flush with the floor line, for convenience in placing sheets or packs upon the doubling table and removing the doubled sheets therefrom.

The parts of the machine which engage and double the sheets are a knife-like bender 6 and two crimping members 7. The bender 6 is mounted upon a pivot pin 8 which extends across a slot 9 formed in a reciprocating bender slide 10, to one end of which is secured, by means of a pivot pin 11, a connecting rod 12 which is also pivoted to a

crank disk 13 driven from any suitable source of power, preferably through a kick-out clutch mechanism which will be described below.

- 5 The bender 6 includes a blade 16 and an enlarged tail portion 17 which acts as a counterweight and tends to hold the blade 16 in horizontal position. The bender is provided with two shoulders 18 and 19 on 10 opposite sides of the pivot pin 8, as best shown in Figs. 2 and 3. The shoulder 18 limits the swinging movement of the bender to the position where the blade is vertical, and the other shoulder 19 limits the downward movement of the blade to the position where this blade is horizontal. Adjacent to the shoulder 19 the bender has a straight surface 20 which acts as a cam to raise the bender member to its vertical position when 15 the slide 10 is moved toward the crimping members. On the edge of the tail portion 17 opposite to the straight surface 20 is a shoulder 21 which is employed to actuate the rack slide and the crimpers during the 20 final doubling operation.

Upon the bed plate 2 is a slotted guide member 25 for the bender slide 10, and also a pair of guide ribs 26 which are arranged in line with the guide member 25 and are wider apart than the sides of the guide member 25. A groove 26^a, Fig. 6, is formed in the bed plate 2 between the guide ribs 26 for the purpose of guiding the lower edge of the bender when the bender is upright. 25 Between the guide ribs 26 is slidably mounted a channeled rack slide 27 having racks 28 formed in or secured to its opposite sides, and having a space 29 between the racks of proper width to slidably receive the bender slide 10. The bender slide 10 rests in the 30 guide member 25 and in the channeled rack slide 27. A slot 30 is formed in the bottom of the rack slide 27 and another and shorter slot 31 is formed in the bed plate 2 immediately beneath the slot 30. The weighted tail portion 17 of the bending member 6 extends through the slots 30 and 31 when the bender blade is in its horizontal position, Fig. 2, and when the slide 10 is moved toward the crimping members 7 the cam portion 20 of the bender engages the rounded end 33 of the slot 31 in the base plate 2, and as the slide 10 advances farther, the cam 35 portion 20 raises the bender blade to its vertical position.

One end of the channeled rack slide 27 rests against a spring 35 which tends to move the rack slide to the right, as shown in the drawing. Another spring 36 extends 40 across the ends of the guide ribs 26 and acts to return the rack slide 27 to its normal position when the end of this slide is caused to project beyond the guides 26 during the first doubling operation. The springs 35 and 36 thus act as centering springs tending

to keep the rack slide 27 in its normal position, at which time the bender 6 is horizontal and the crimpers 7 are in the starting position shown in Figs. 4 and 6. The rack slide, however, is free to slide lengthwise in either direction when forced to do so by the movements of the bender slide 10, as will be more fully described below.

Each of the crimping members 7 has a curved working surface 41 and a straight surface 42. Figs. 1 to 9 of the drawing show the working surfaces 41 as being somewhat longer than is required for engaging and crimping the sheets. Since only a portion of the working surfaces 41 are brought into actual contact with the work, these surfaces may be much reduced, as shown for example at 41^a in Fig. 10, in which case the crimping members are wedge shaped in cross-section. The lower end of each crimping member is reduced in diameter to form a neck 43 to which is secured a pinion 44. As shown, the pinion 44 is secured in place by means of a collar 45 carried by a pivot pin 46 projecting from the neck 43. The collar 45 and the pin 46 fit within bearing recesses formed in the base plate 2. The guide ribs 26 are cut away, as shown at 48, to admit the pinions 44 into engagement with the teeth in the racks 28 of the rack-slide 27.

The upper ends of the crimping members 7 are provided with pivot pins 50 which extend through openings in a transverse arm 52 which is carried at the upper ends of vertical standards 53 which rise from the base plate 2.

When packs of sheets are brought to the doubler, the sheets are frequently out of alignment and their edges are usually more or less ragged. For the purpose of matching the sheets and raising them upon their edges in front of the crimping members, I provide two pairs of gage arms 55 and 56. The arms 55 lift the sheets to an edgewise vertical position in front of the crimping members, where the sheets arrange themselves vertically by gravity, and then the gages 56 move horizontally inward and align the sheets horizontally as nearly as possible. Both sets of gages are operated from a horizontal shaft 57 mounted in bearings 58 in the bed plate 2. The gages 55 which raise the sheets to vertical position normally rest in grooves 59 in the surface of the doubling table, and are extended beneath the doubling table 3 through openings 60, Fig. 1. Below the doubling table each of the gage arms 55 is bent to form a pivot section 61 which is received in a bearing 62, the end of this pivot section beyond the bearing 62 being bent downward to form a crank 63. Connecting rods 65 connect the cranks 63 with cranks 66 carried by the horizontal operating shaft 57, to

which is also secured an operating lever 67 or other suitable operating means, which may be operated either manually or by power.

5 The side gage arms 56 are carried by vertical shafts 70 which are loosely mounted in fixed bearings, and which carry cranks 71 and 72 joined by a connecting rod 73, the cranks and connecting rod being so arranged that when one of the vertical shafts 70 is rocked the other shaft will rock equally and in the opposite direction. One of the shafts 70 is provided with a second crank 74 joined by a connecting rod 75 to an operating lever 76 which is mounted loosely on the shaft 57. The operating levers 67 and 76 may be either hand levers, treadles or power-operated cranks, and may suitably be connected together to move in the proper sequence.

The machine is preferably arranged to stop after making one complete cycle of operations, and for this purpose the crank disk 13 is made to stop after completing one full revolution. One method by which this may be done is shown in Figs. 1 and 2, where the crank disk 13 is shown mounted on a short vertical shaft 80 which carries a bevel gear 81 driven by a similar bevel gear 82 on a horizontal shaft 83 which is mounted in bearings 84 beneath the bed plate 2, and which carries a kick-out clutch mechanism shown in Fig. 1. This clutch mechanism consists of a toothed clutch member 85 which is loosely mounted on the shaft 83 and a movable clutch member 86 which is slidably keyed upon the shaft 83. The clutch member 85 is formed integral with, or rigidly secured to, a gear wheel 87 which is loosely mounted on the shaft 83 and driven continuously by means of any suitable power connections, not shown. A spring 88 is compressed between the sliding clutch member 86 and a collar 89 on the shaft 83, and tends to force the clutch member 86 into engagement with the clutch member 85. The sliding clutch member 86 carries a cam member 90 which is engaged by a pin 91 that extends through a stationary bracket 92 and is normally forced down into the path of the cam 90 by the weight of an arm 93 to which the pin 91 is secured.

The arm 93 is carried by a pivot pin 94 mounted on the bracket 92, and the pivot pin 94 is provided with an operating lever 95 which may be a treadle or a hand lever, and which, when depressed by the operator, acts through the arm 93 to raise the pin 91 from the path of the cam 90. The spring 88 then forces the member 86 into engagement with the constantly rotating clutch member 85, thereby causing the shaft 83 to rotate with the gear wheel 87. The crank disk 13 is thus set in motion and operates the various mechanisms described above.

As the shaft 83 nears the end of its rotation the cam 90 engages the stationary pin 91 which meanwhile has been returned to its active position as soon as the lever 95 is released. The engagement between the cam 90 and the pin 91 withdraws the clutch member 86 from the clutch member 85, with the result that the shaft 83 makes one complete revolution and then stops. Since the bevel gears 81 and 82 are of the same diameter, a single rotation of the shaft 83 produces one complete rotation of the crank disk 13, so that the machine always starts and stops with the parts in the same position, which is shown in Fig. 4, and in which the sheet-receiving surfaces 42 of the crimping members 7 are in their aligned position.

At the beginning of the operation of the machine, the crimping members 7, as just stated, are arranged with their straight surfaces in line with each other, as shown on Fig. 4, forming a vertical wall to receive the sheets to be doubled. The bender 6 is in its horizontal position, the gauge arms 55 are in their grooves 59, below or flush with the surface of the doubling table, and the gauge arms 56 are opened. The sheet or pack of sheets is brought to the doubling table and laid flat upon the table near the crimping members. The lever 67 is then operated to raise the gauges 55, thus bringing the sheets to vertical position, as shown at A, Fig. 7, where they rearrange themselves vertically by gravity if they are not already correctly matched. Then the lever 76 is operated to close the gauge arms 56 upon the side edges of the sheets so as to align the sheets horizontally. When the sheets are in proper vertical position in front of the crimping members, the operator depresses the treadle or hand-lever 95, thereby releasing the clutch member 86 in the manner described above and setting the crank disk 13 in rotation, which causes the bender slide 10 to advance toward the crimping members. As the slide 10 advances, the cam surface 20 of the bender engages the rounded end 33 of the slot 31 in the bed plate, thus raising the blade of the bender to the vertical position shown in dotted lines, Fig. 3. With the blade in this vertical position, the bender approaches the sheets as shown in Fig. 7, and engages the sheets along the vertical line of doubling. The sheets are thus clamped between the flat faces 42 of the crimping members and the vertical blade of the bender. The bender continues to advance between the crimping members and this continual movement of the bender forces the sheets to bend along the line of doubling and forces the bent portion B of the sheets between and beyond the crimping members. This action of the bender and the sheets causes the crimping members to rotate upon their axes, giving a

space between the crimping members into which the fold B in the sheets is forced by the bender member, as shown in Fig. 8.

This rotation of the crimping members acts through the pinions 44 and the teeth of the racks 28 to advance the end of the rack slide 27 beyond the ends of the guide ribs 26. The forward end of the bender slide 10 also advances beyond the end of the guide ribs 26, and deflects the spring 36. The position of the various parts of the machine at this time is shown on Fig. 5.

The effective radius of the crank disk 13 is such that when the bender has passed beyond the crimping members sufficiently to deliver the fold B in the sheets well between the crimping members, the slide 10 is withdrawn, carrying with it the bender 6, which falls to its horizontal position, as soon as it reaches the registering slots 30 and 31 in the rack slide 27 and in the bed plate 2. The continued rotation of the crank disk to the position shown in Fig. 2 brings the depending shoulder 21 of the bender to the end of the slot 31 in the rack slide 27 and causes the rack slide to travel rearwardly with the bender slide 10. This rearward movement of the rack slide acts through the pinions 44 to rotate the crimping members on their pivots, from the open position of Figs. 5 and 8 to the position of Fig. 9 and thence to the final position shown in full lines on Fig. 1 and in dotted lines on Fig. 9, thus causing the segmental working surfaces of the crimping members to rock together, compressing the fold previously made by the bender and effectively doubling the sheets. This rocking movement of the crimping members also delivers the doubled sheets upon the doubling table, where they are ready to be removed and replaced by a new pack of sheets. The crank disk 13 continues to rotate until it makes one complete revolution and reaches the position shown in Fig. 4, when the cam 90 of the kick-out clutch withdraws the movable clutch member 86 from the fixed clutch member 85 and stops the crank disk and the bender slide 10. During the latter part of its movement, the crank disk 13 causes the bender slide to move forward toward the crimpers, and the rack slide is then moved by its spring 35 from the position of Fig. 1 to the position of Fig. 4. This movement of the rack slide acts through the rack teeth 28 and the pinions 44 to restore the crimpers to their starting position, as shown in Fig. 4.

Numerous changes in the construction and arrangement of parts may be readily made without departing from my invention as set forth in the appended claims.

I claim as my invention:

1. In a doubling machine, the combination of two cooperating pivotally mounted

segmental crimping members, means for bending the sheet to be doubled along the line of doubling and for inserting the bent fold of said sheet between and beyond said crimping members when in retracted position, and means for operating said crimping members to advance them and compress said fold.

2. In a doubling machine, the combination of two cooperating crimping members, means for bending the sheet to be doubled along the line of doubling and for inserting the bent fold of said sheet between said crimping members, and means operable by said bending means during withdrawal thereof from bending position for operating said crimping members to compress said fold. 75

3. In a doubling machine, the combination of two crimping members arranged to rock in cooperation, means for bending the sheet to be doubled along the line of doubling and for inserting the bent fold of said sheet between said crimping members, and means operable by said bending means during withdrawing thereof from bending position for rocking said crimping members to compress said fold. 85

4. In a doubling machine, the combination of two segmental crimping members arranged to rock in cooperation, means including the said crimping members for making an initial fold in the sheet to be doubled along the line of doubling and for inserting the bent fold of said sheet between and beyond said doubling members, and means for rocking said crimping members to compress said fold. 95

5. In a doubling machine, the combination of two segmental crimping members arranged to rock about fixed pivots in cooperation, means including the said crimping members for making an initial fold in the sheet to be doubled along the line of doubling, means for pivotally rocking said crimping members to admit said fold between them, and means for rocking said crimping members in reverse direction to compress said fold. 105

6. In a doubling machine, the combination of two crimping members having co-operation curved working surfaces and also having flat sheet-receiving surfaces, means for engaging the sheet to be doubled along the line of doubling while said sheet is resting against said flat sheet-receiving surfaces, and for causing the said sheet to bend along the line of doubling and causing the bent fold so produced to enter between said crimping members, and means for rocking said crimping members to compress said fold. 115

7. In a doubling machine, the combination of two crimping members having co-operating curved working surfaces, pinions 120

carried by said crimping members, racks engaging said pinions, means for producing an initial fold in the sheet to be doubled along the line of doubling and for forcing the said fold between said crimping members, thereby rocking said crimping members on their pivots and moving said racks lengthwise, and means for moving said racks lengthwise in the reverse direction, thereby rocking said crimping members in the reverse direction upon their pivots and causing said crimping members to compress said fold.

8. In a double machine, the combination of two crimping members having cooperating curved working surfaces, pinions carried by said doubling members, racks engaging said pinions, fold-forming means for producing an initial fold in the sheet to be doubled along the line of doubling and for forcing the said fold between said crimping members, thereby rocking said crimping members on their pivots and moving said racks lengthwise, and means actuated by said fold-forming means for moving said racks lengthwise in the reverse direction, thereby rocking said crimping members in the reverse direction upon their pivots and causing said crimping members to compress said fold.

9. In a doubling machine, the combination of two oscillating crimping members having cooperating segmental working surfaces movable toward and from each other and a bender movable through and beyond the space between said crimping members when they have been moved apart.

10. In a doubling machine, the combination of two crimping members mounted for oscillation on parallel axes and having cooperating segmental working surfaces, and a bender movable between and beyond said crimping members in a direction perpendicular to the plane including the axes of said crimping members.

11. In a doubling machine, the combination of two crimping members mounted for oscillation on parallel axes and having cooperating segmental working surfaces, and a bender comprising a blade adapted to reciprocate between and beyond said crimping members in a direction perpendicular to the plane including the axes of said crimping members.

12. In a doubling machine, the combination of two crimping members mounted for oscillation on parallel axes and having cooperating curved working surfaces and flat sheet-receiving surfaces adapted for alinement parallel to the plane including the axes of said crimping members, and a bender comprising a blade movable between said crimping members in a direction perpendicular to the plane including the axes of said crimping members.

13. In a doubling machine, the combination of two cooperating crimping members mounted for oscillation on vertical axes, a bender comprising a pivotally movable blade adapted to move horizontally between said crimping members, and means for raising said blade to vertical position before passing between said crimping members, and for causing said blade to assume a horizontal position when removed from said crimping members.

14. In a doubling machine, the combination of two cooperating crimping members mounted for oscillation on vertical axes, a bender mounted for horizontal reciprocation between said crimping members, said bender comprising a blade, means for raising said blade to vertical position while moving toward said crimping members and for maintaining said blade in vertical position while passing between said crimping members, and means for causing said blade to assume a horizontal position after being withdrawn from between said crimping members.

15. In a doubling machine, the combination of two cooperating crimping members mounted for oscillation on vertical axes, and bending mechanism including a horizontal slide, means for reciprocating said slide lengthwise, a blade pivotally carried by said slide and adapted to reciprocate between said crimping members, means for raising said blade to vertical position while said slide is advancing toward said crimping members and for returning said blade to horizontal position while said blade is moving away from said crimping members.

16. In a doubling machine, the combination of two cooperating crimping members mounted for oscillation on vertical axes, and bending mechanism including a horizontal slide, means for reciprocating said slide lengthwise, a blade pivotally carried by said slide and having a weighted portion tending to hold said blade in horizontal position, and means for engaging the said weighted portion and for raising said blade while the said slide is moving to carry said blade toward said crimping members.

17. In a doubling machine, the combination of two crimping members mounted for oscillation on vertical axes and having flat vertical sheet-receiving surfaces, pinions carried by said crimping members, a rack slide having teeth engaging both of said pinions, means for reciprocating said rack slide lengthwise, and spring means tending to hold said rack slide in the position wherein the said sheet-receiving surfaces of said crimping members are in alinement.

18. In a doubling machine, the combination of two crimping members mounted for oscillation on vertical axes and having flat vertical sheet-receiving surfaces, pinions

- carried by said crimping members, a rack slide having teeth engaging both of said pinions, means for reciprocating said rack slide lengthwise, spring means tending to hold said rack slide in position wherein the said sheet-receiving surfaces of said crimping members are in alinement, a bender slide disposed in a longitudinal slot in said rack slide, a bending blade pivotally carried by said bender slide and adapted to reciprocate between said crimping members, power connections for reciprocating said bender slide lengthwise, and means for causing said rack slide and said bender slide to move in unison during a portion of the movement of said bender slide which withdraws said bending blade from between said crimping members.
19. In a doubling machine, the combination of two crimping members mounted for oscillation on vertical axes and having flat sheet-receiving surfaces, pinions carried by said crimping members, a rack slide having teeth engaging both of said pinions, means for reciprocating said rack slide lengthwise, spring means tending to hold said rack slide in the position wherein the said sheet-receiving surfaces of said crimping members are in alinement, a bender slide disposed in a longitudinal slot in said rack slide, a bending blade pivotally mounted on said bender slide and unbalanced so as to normally rest horizontally, said blade having a portion depending through slots in said bender slide and in said rack slide, and stationary means for engaging said depending portion of said blade during the forward movement of said bender slide, and for thereby raising said bending blade to vertical position, the said depending portion of said blade being adapted, during the rearward movement of said bender slide, to engage said rack slide and move said rack slide in unison with said bender slide.
20. In a doubling machine, the combination of cooperating crimping members mounted for oscillation on vertical axes, gage arms for raising sheets into vertical position adjacent to said crimping members, and other gage arms movable to aline said sheets horizontally.
21. In a doubling machine, the combination of a doubling table, two cooperating crimping members mounted for operation on vertical axes, gage arms received in slots in said table, means for rocking said gage arms on a horizontal axis to raise sheets into vertical position adjacent to said crimping members, and gage arms adapted to approach each other horizontally and to aline the said vertical sheets.
22. In a doubling machine, the combination of oscillatory crimping members having cooperating segmental working surfaces, bending means for advancing a sheet between adjacent ends of said segmental surfaces when in advanced position to form a fold therein, and means for retracting said crimping members about their respective pivots to compress said fold and to discharge the sheet, the folded edge of the sheet having been advanced a distance less than the length of said segmental surfaces.

In testimony whereof I, the said LAWRENCE C. STEELE, have hereunto set my hand.

LAWRENCE C. STEELE
